CLAIM

The ornamental design for spout, as shown and described.

DESCRIPTION

FIG. 1 is a perspective view of our new design of a spout; FIG. 2 is a front elevational view of our new design of the spout;

FIG. 3 is a rear elevational view of our new design of the spout;

FIG. 4 is a right elevational view of our new design of the spout;

FIG. 5 is a left elevational view of our new design of the spout;

FIG. 6 is a top plan view of our new design of the spout; and,

FIG. 7 is a bottom plan view of our new design of the spout. The broken line representation in the drawings of the faucet base, handle and spout (partial) is for illustrative purposes only and forms no part of the claimed design.
